[57] CLAIM

The ornamental design for a cover for tree injectors, as shown and described.

DESCRIPTION

FIG. 1 is a front elevational view of my new design wherein the front and rear sides are identical;

FIG. 2 is a top plan view of the design of FIG. 1;

FIG. 3 is a bottom plan view of the design of FIG. 1; and,
FIG. 4 is a side elevational view of the design of FIG. 1
wherein the right and left side views are identical.

The dashed line showing of sighting windows in the top and bottom plan views are for illustrative purposes only and form no part of the claimed design.

The dashed line showing of cover tabs in the views of FIGS. 1-4 are also for illustrative purposes only and form no part of the claimed design.
